UNITED STATES PATENT OFFICE.

MARIE U. DIXEY, OF NEW YORK, N. Y.

VEIL.

1,141,581.

Specification of Letters Patent.

Patented June 1, 1915.

Application filed May 20, 1914. Serial No. 839,788.

To all whom it may concern:

Be it known that I, MARIE U. DIXEY, a citizen of the United States, residing at New York, in the county of New York and State 5 of New York, have invented certain new and useful Improvements in Veils, of which the following is a specification.

My invention relates to improvements in ladies' veils, and consists in providing such 10 an article of apparel with a permanently formed pocket preferably woven therein to receive the chin, and in some instances the nose of the wearer.

As almost all women know, more or less 15 inconvenience is experienced in wearing veils, due to the manner in which the lower portion thereof fits about the chin of the wearer. Ordinarily such lower portion extends downwardly below the chin, in an un- 20 secured manner, with the result that the lower edge of the veil rides upon and off of the chin. To overcome this disadvantage, some women draw their veils, particularly the lower longitudinal edge thereof, exces- 25 sively tight, with the result that great incon- 30 venience is caused the wearer, and the veil invariably soon tears or gives way, most frequently at the lower edge thereof, and at various other points. Another method re- 35 sorted to from the necessity of the case, is to twist the portion of the veil which is adapt- 40 ed to be arranged below the chin after the same is applied, to form a knot therein, with a view of shortening the lower edge of the 45 veil, to form a stop, as it were, to engage the chin and prevent the veil from riding upon and off of the chin. This method has been found to be even more destructive of the veil than the excessive longitudinal pull, 50 while the appearance of the same is materially damaged.

As far as I am aware, no one, not even a woman with her familiarity with the veil, has devised satisfactory means to overcome 55 the above referred to disadvantages. Such means, to be satisfactory, must obviously be simple and inexpensive, and adapted not to mar or perceptibly alter the appearance of the veil. Now, I have discovered that the 60 problem may be wholly satisfactorily solved, by providing the veil, preferably adjacent its lower edge, with a permanent outwardly bulging pocket, to receive the chin. This pocket is preferably formed by weaving the 65 fabric at that point, to produce an outward bulge or pocket.

In the accompanying drawing, forming a part of this specification and in which like numerals are employed to designate like parts throughout the same Figure 1 is a perspective view of the veil in use. Fig. 2 is an enlarged elevation of the pocket portion of the veil, and Fig. 3 is a perspective view of the veil removed, and flattened.

In the drawings, wherein is shown a preferred embodiment of my invention, the numeral 10 designates my veil as a whole, formed of a suitably woven net, including longitudinal and transverse threads or strands 11 and 12, as shown. The veil 10 is 65 provided with a lower longitudinal selvage edge 13, preventing the net from unraveling.

The numeral 14 designates an outwardly bulging pocket, embodying, when the veil is in use an approximately horizontal bottom wall 15, which is arranged below and engages with the chin, preventing the upward movement of the veil with relation thereto. This outwardly bulging pocket 14 is formed by weaving the material of the 70 veil to produce the same, which may be accomplished in various manners, as will be found more advantageous by the manufacturers, in the production of the articles. One way of forming the same is to lengthen 75 portions 16 and 17 of the longitudinal and transverse interwoven threads 11 and 12, whereby they can bulge outwardly to provide the pocket.

Having described my invention, I claim: - 90
1. As an article of manufacture, a veil comprising a section of normally substantially transversely flat woven net having its upper and lower longitudinal edges of substantially the same length, and provided 95 above and adjacent the lower longitudinal edge with a relatively short outwardly bulging pocket approximately equi-distantly spaced from the opposite ends of the lower longitudinal edge of the veil with the lower 100 flat portions of the veil extending beyond the pocket upon opposite sides thereof for substantial distances.

2. As an article of manufacture, a veil comprising a section of normally substantially transversely flat woven net, provided above and near its lower longitudinal edge with a relatively short outwardly bulging pocket with flat portions of the veil extending beyond the pocket upon opposite sides 105 110 thereof for substantial distances.

3. As an article of manufacture, a veil

comprising a section of normally flat woven net provided near its lower longitudinal edge with an outwardly bulging pocket restricted to the substantially central portion 5 of the veil with flat portions of the veil extending beyond the pocket upon opposite sides thereof for substantial distances.

In testimony whereof I affix my signature in presence of two witnesses.

MARIE U. DIXEY.
